UNITED STATES PATENT OFFICE.

LAURENCE LOUIS LIMOGES, OF SIOUX CITY, IOWA.

FOLDING LUGGAGE-CARRIER.

1,393,294.

Specification of Letters Patent. Patented Oct. 11, 1921.

Application filed March 6, 1920. Serial No. 363,901.

To all whom it may concern:

Be it known that I, LAURENCE L. LIMOGES, a citizen of the United States, residing at Sioux City, in the county of Woodbury and 5 State of Iowa, have invented new and useful Folding Luggage-Carriers, of which the following is a specification.

This invention relates to carriers for baggage or the like of the type designed especially for the running boards of automobiles.

An object of the invention is to provide in such a carrier means by which it may be securely clamped to a running board and thereafter can be adjusted to any angle desired with respect to the body of the car, whereby different sizes and shapes of luggage may be accommodated.

Another object is to construct such a carrier with sides and make the carrier foldable or collapsible not only lengthwise but sideways whereby the carrier will hold the luggage independently of the fenders of the automobile and yet may be collapsed into a compact package which may be put in a space too small for the ordinary carriers.

Another object is to provide means by which luggage may be carried even though the luggage be piled high above the top of 30 the carrier.

General objects are to provide a device of the character described which is adaptable not only to the running boards of all types of cars but may be used in connection with shelves, tables, or similar supports and which is therefore of general utility.

The invention will be best understood from a consideration of the following detailed description taken in connection with 40 the accompanying drawing forming part of this specification, with the understanding, however, that the invention is not confined to any strict conformity with the showing in the drawing but may be changed and modified so long as such changes and modifications mark no material departure from the salient features of the invention as expressed in the appended claims.

In the drawing:

50 Figure 1 is an elevation of an embodiment of the invention shown in place on the running board of an automobile.

Fig. 2 is an end elevation of the carrier shown in clamped position upon the running 55 board; the latter being shown in section.

Fig. 3 is an elevation from the side opposite to that illustrated in Fig. 1, showing the carrier collapsed.

Fig. 4 is a side view of the same.

Fig. 5 is a side view of the intermediate 60 clamp.

A running board 5 of an automobile (not shown), which running board may be taken as indicative of any support, provides means upon which the device of the invention is 65 held. The carrier includes a framework or rack made of lazy tongs, uprights secured to the ends of the lazy tongs in such a way that free expansion or collapsing of the same is permitted, clamps secured to the uprights 70 and to the lazy tongs, and foldable or collapsible sides connected with the uprights and the adjacent clamps.

The lazy tongs are made of flat bars 6 pivoted to each other as at 7, the construction 75 being so well known as to require no further description. At each end of the lazy tongs an upright, a foldable side, and an adjustable clamp are provided so that a description of the parts at one end of the lazy tongs 80 will be sufficient.

The upright 8 is tapered toward its upper end as seen in Figs. 2 and 3, and there has an integral loop 9 through which a strap 10 may be run. Also integral with the upright 85 8 and the loop 9 is a guide 11 which provides means whereby the upright may be connected with the lazy tongs and yet permit free expansion or collapsing of the same. Slides 12 are mounted on the guides 11 and are 90 pivotally connected as at 14 to the upper end of one of the end bars 6. The lower end of the other end bar is pivotally connected as at 14^a with a lug 13 formed integrally with the upright 8 and extending inwardly 95 from a point near the extreme end thereof. When the carrier is expanded the slides 12 will move to the lower end of the guides 11, and when it is collapsed they will move to the upper ends thereof, as shown in Fig. 3. 100

The sides of the carrier comprise a pair of flat bars 16 and 17 pivotally connected at their ends to each other as indicated at 18. The other end of the bar 16 is pivotally connected as at 15 to the adjacent upright 8. 105 The other end of the bar 17 is pivotally connected as at 20 near the outer end of the arm 19 of the clamp. The arm 19 carries bearing plates 21 and 23 to permit the carrier to be supported firmly upon the run- 110

ning board. These plates are perfectly circular in outline, as shown, the plate 21 being formed at the free end of the arm 19 of the clamp while the plate 23 is formed near the 5 opposite end of said arm. The plate 21 has an integral loop 22 to receive a strap 10, this loop being similar to the loop 9.

The extreme lower end of the upright 8 has a serrated disk or ratchet plate 24 10 formed integrally therewith adapted to coöperate with a similar plate or disk 25 formed upon the end of an arm 26 of the clamp. A bolt provides means whereby the clamp and the upright may be swung relatively to each other, said bolt passing through both of the disks or plates and carrying a wing nut 28 or similar means to clamp the serrated faces of the plates together to hold the carrier in any adjusted 15 position relatively to the clamps. Two such positions are indicated in dotted lines in Fig. 2. When the nuts 28 are loosened, the carrier and the clamps which support the carrier may be swung relatively to each 20 other, but when the nuts are tightened the clamps and the carrier body will be rigid with respect to each other. This swinging of the carrier body causes a change in the position of the sides and permits the accommodation of bundles and baggage of widely 25 varying sizes and shapes. The free end of the lower arm 26 of the clamp has a thumb screw 27 or similar device adapted to press against the under side of the running 30 board or shelf to coöperate with the plates 21 and 23 in holding the carrier firmly in place. It will be noted that the free end of the arm 26 is approximately half-way between the plates 21 and 23 so that the pressure exerted by the screw 27 is distributed 35 about equally.

At a mid-point of the lazy tongs and connected to one of the lower pivots 7 so as to be rigid with respect to the lazy tongs, 40 is a strap 29 appropriately shaped to support an intermediate clamp 30 of smaller dimensions than those clamps associated with the ends of the carrier. This intermediate clamp is illustrated in Fig. 5 and comprises an upper arm 32 having a bearing plate at its free end and a lower arm 33, a pivotal element 31 connecting the clamp with the strap 29, allowing free turning of the clamp. The outer end of the arm 33 has a 45 thumb screw 34 similar to the thumb screws 27. While the intermediate clamp can be freely moved forwardly to collapsible position, as shown in Fig. 3, and has no means for holding it in an adjusted position relative to the carrier, it would not involve invention to provide a pair of ratchet faces and clamping screw in place of the simple pivotal element 31 which is shown.

At a mid-point of the lazy tongs and also 50 directly above the clamp 31 is a pivotally

mounted strap 35 having a loop similar to the loops 9 and 22 to receive one of the straps 10. More than one of the upper pivotal elements of the lazy tongs might be provided with these strap loops and I do not 55 wish to be limited to the precise construction shown. The straps 10 are designed to pass up from the carrier to some portion of the automobile, such as the brackets of the top of the car or to other convenient 60 parts. These straps when so fixed will allow the use of the carrier to hold baggage of great bulk, and will permit mounting of suit cases or other articles, one on top of the other, as high up along the sides of the car 65 as may be desired. By swinging the upright arms into various positions, and by changing the length of the straps, it will be possible to accommodate almost any size of bundle that it is safe to carry in such a 70 position. The bulky part of the luggage can be carried higher than the running board, thus allowing more clearance space when driving through brush or in narrow 75 lanes.

Another feature of the invention is the folding or collapsing of the sides. These sides hold the luggage away from the fenders of the car which is an advantage, 80 since many articles will scratch the paint 85 off the fenders and soon make the car look very shabby.

What is claimed is:

1. A folding luggage carrier comprising running board clamps, uprights pivotally 100 connected with the running board clamps above the running board, a readily collapsible rack connected to the uprights, and bars pivotally connected to each other and to the uprights and clamps to form sides for the 105 carrier, said rack being prevented by the sides from swinging below the running board.

2. A folding luggage carrier comprising running board clamps, uprights pivotally 110 mounted on the running board clamps above the running board, a folding rack connected to the uprights, folding sides each comprising a pair of bars pivotally connected to each other and to the uprights and clamps, 115 said bars having a length such that they extend in obtuse angular relation to each other when the uprights are vertical, and means for holding the rack structure in the desired angular position with respect to the running board with said rack being in all positions 120 above the running board.

3. A folding luggage carrier comprising running board clamps, uprights pivotally mounted upon the running board clamps, 125 means for maintaining the uprights in adjusted angular position relative to the clamps, a folding rack structure joining the uprights, and folding sides each comprising a pair of bars pivotally connected 130

to each other and to the uprights and clamps, said bars having a length such that they extend in obtuse angular relation to each other when the uprights are vertical.

5. 4. A folding luggage carrier comprising running board clamps, uprights pivotally mounted on the running board clamps above the running board, a folding rack connected to the uprights, and means for holding the 10 rack structure in the desired angular position with respect to the running board, said clamps each comprising a long arm adapted to lie over the running board and having a pair of plates bearing against the running board and a short arm adapted to lie under the running board and having a clamping screw at its outer end, the clamping screw bearing against the running board between the two plates, whereby the clamping pressure is about equally divided between the plates, 15 uprights pivotally connected with the clamps above the running board, a rack connected to the uprights, and folding sides 20 each comprising a pair of bars pivotally connected to each other and to the uprights and clamps, said bars having a length such that they extend in obtuse angular relation to each other when the uprights are vertical.

5. A folding luggage carrier comprising running board clamps, said clamps each

comprising a long arm adapted to lie over the running board and having a pair of plates to bear upon the running board, and a short arm adapted to lie under the running board and having a clamping screw at its free end, the clamping screw bearing against the running board between the two plates whereby the clamping pressure is about equally divided between the plates, uprights pivotally connected with the clamps above the running board, a rack connected to the uprights, and folding sides 35 each comprising a pair of bars pivotally connected to each other and to the uprights and clamps, said bars having a length such that they extend in obtuse angular relation to each other when the uprights are vertical. 40

In testimony that I claim the foregoing as my own, I have hereto affixed my signature.

LAURENCE LOUIS LIMOGES.
